AMMONIUM NITRATE-HYDROCARBON OIL
EXPLOSIVE COMPOSITION

Joseph F. Wilson, Bartlesville, Okla., assignor to Phillips
Petroleum Company, a corporation of Delaware
No Drawing. Filed Dec. 23, 1963, Ser. No. 332,866
3 Claims. (Cl. 149—46)

This invention relates to a novel ammonium nitrate explosive. In another aspect, it relates to a method of preparing an ammonium nitrate explosive. In a further aspect, it relates to an improved method of producing an explosion.

The use of ammonium nitrate in admixture with fuel oil or diesel oil as a low-grade explosive is becoming increasingly widespread in open pit and underground mining, quarrying, seismic exploration, and construction of pipeline trenches, roads, railways, etc. Such an explosive can be readily prepared in small batches in the field or can be prepared on a large scale with bulk mixing equipment and stored or aged in warehouses.

The use of ammonium nitrate explosives of this type, usually consisting of a mechanical mixture of 94 weight percent fertilizer-grade ammonium nitrate and 6 weight percent fuel oil or diesel oil, has encountered certain problems due to the nature of the oil component. The oils normally used in making such explosives have a volatility which causes a loss of oil from the mixture through volatilization of the oil component upon storage or transit of the mixture. Such volatility gives rise to objectionable odor from the ammonium nitrate explosive mixture, particularly in confined areas where the mixtures are stored or used, for example warehouses and underground mines. The loss of oil from these mixtures prior to their use also causes a shift in the carbon-oxygen balance which adversely affects the total energy released when such explosives are detonated and an increase in the quantity of the toxic reddish-brown fumes (oxides of nitrogen), which fumes are particularly obnoxious and hazardous when such explosives are used in underground mines where the air or atmosphere must be closely controlled and kept as pure as possible. A further problem attendant the use of such oils in making ammonium nitrate explosives is the discoloration that many of these oils impart to the ammonium nitrate when mixed therewith, which discoloration detracts from the sales appeal of the oil and explosive made therewith.

Accordingly, an object of this invention is to provide an improved ammonium nitrate explosive composition. Another object is to provide a method of preparing such ammonium nitrate explosive composition. Another object is to prepare a method of generating an explosion using such an explosive. Another object is to overcome the problems normally encountered when ammonium nitrate is mixed with fuel oil, diesel oil, or the like due to the volatility of such oils. Further objects and advantages of this invention will become apparent to those skilled in the art from the following description and accompanying claims.

I have now discovered an improved ammonium nitrate explosive can be prepared by admixing particulate am-

2

monium nitrate with a normally liquid hydrocarbon oil meeting the following specification:

Pour point, ° F. maximum	<50
Flash point, ° F. minimum	>250
Viscosity, SUS at 100° F.	30 to 125
API gravity	24 to 45
ASTM color	<3

Aromatics, acid treated, volume percent

Sulfur content, weight percent

Nitrogen content, weight percent

Bromine number

Ammonium nitrate explosives made with oils meeting

such specifications exhibit little if any loss of the oil com-

ponent at the ambient conditions normally encountered by ammonium nitrate explosives. As a result, little if any obnoxious and potentially hazardous oil vapors or odor will be encountered in the preparation, storage, trans-

it, or use of such explosives, and the carbon-oxygen bal-

ance necessary to realize the desired blasting or explosive

properties of the explosive will not be disturbed. The

explosives of this invention are relatively low in cost

and can be readily prepared in the field or on a large

scale for use in any of the aforementioned mining, con-

struction, etc.

The ammonium nitrate used in preparing the explosives of this invention is particulate in form, e.g., granules, prills, etc. I prefer to use it in the form of prills, such as that prepared by spraying hot ammonium nitrate from

the top of the tower and allowing the droplets to descend in a countercurrent stream of air at a lower tempera-

ture and form porous aggregates or prills of microcrystals,

usually about $\frac{1}{16}$ to $\frac{3}{32}$ of an inch in diameter. Such

prills can be coated, if desired, with suitable conditioning

agents to improve their storage stability, such as dia-

tomaceous earth, kaolin, etc. An especially useful condi-

tioning agent is an admixture of kaolin and a small

amount of an alkylaryl sulfonate, e.g., Petro-Ag. The

ammonium nitrate can be of fertilizer grade with a size

of 10 to 14 mesh (U.S. sieve).

The ammonium nitrate is mechanically mixed with any

one or a mixture of the oils meeting the specification set

forth above, these oils being available from many pe-

trolium refinery streams. Any suitable mixing technique

can be used, such as that currently being employed for

ammonium nitrate-fuel oil or ammonium nitrate-diesel

oil explosives. For example, such mixing can be done

in the field or on the job in small batches in a tub or

other suitable container and the mixture then poured in

a bore hole, or the oil can be sprayed on the ammonium

nitrate as it flows through a funnel into the bore hole, or

the oil can be poured in open bags of the ammonium

nitrate and used as prepared or after several hours or

days to allow the oil to diffuse into the ammonium nitrate.

Alternatively, large batches can be prepared with bulk

mixing equipment and the mixture stored or aged before

use. The relative amounts of ammonium nitrate and oil

used in making the explosives of this invention are the

same as that now generally used to make ammonium ni-

trate explosives. Broadly, the ammonium nitrate is mixed

with at least a stoichiometrically equivalent amount of

the oil. Generally, the improved explosives of this in-

vention will comprise 2 to 8 weight percent of the spe-

cified oil and from about 92 to 98 weight percent am-

monium nitrate, based on the total weight of the explo-

sive. Preferably, the explosive will contain from about 4 to 6 weight percent of the specified oil and 94 to 96 weight percent of the ammonium nitrate. These two components, the oil and ammonium nitrate, are the only essential components of the explosives of this invention; however, other materials normally used or found in ammonium nitrate-diesel oil explosives can be incorporated, such as the aforementioned ammonium nitrate conditioning agents, e.g., to prevent caking, sensitizers, e.g.

The detonation of the ammonium nitrate explosives of this invention, which are cap-insensitive, can be accomplished by any of the conventional techniques now used for detonating ammonium nitrate explosives. For example, detonation can be accomplished with a high explosive primer or booster, such as one or more sticks of dynamite, attached to a line of Primacord or other detonating fuse or to a high power electrical cap, e.g., No. 8 cap.

The objects and advantages of this invention are further illustrated in the following examples, but it should be understood that the various details of these examples are not to be construed to unduly limit this invention.

EXAMPLES

A series of runs were carried out in which mixtures of prilled ammonium nitrate and various oils were formed and subjected to certain evaluation tests. The ammonium nitrate used was fertilizer-grade prills. In each run, 94 parts by weight of the prilled ammonium nitrate was mechanically mixed with 6 parts by weight of the candidate oil. The ammonium nitrate-oil mixtures were allowed to stand until the oil had been absorbed on the prilled ammonium nitrate, and a portion of each of the mixtures was sealed in a closed bottle and stored at room temperature, approximately 72 to 76° F. From time to time the bottle was opened and the presence or absence of odor, and its strength, above the explosive mixture was rated. At the same time, the color of the mixture was observed and rated. A sample of each mixture was also tested for loss of oil by evaporation. In this latter test, 100 g. of the mixture was placed in a pan so as to have a bed depth of about $\frac{3}{4}$ inch and an exposed area of about 20 square inches. Air at about 76° F. was then blown across the bed at about 300 linear feet per minute. The weight percent of the oil lost from the sample at the end of 15, 45, 75 and 100 hours was determined.

The specification of the oils used in these tests is given below in Table I, while the results of these evaluation tests are shown below in Table II.

Table I

	Oil sample					
	1	2	3	4	5	6
Pour point, ° F., max.	+10	+5	+35	+10	+40	+35
Flash point, ° F., min.	270	390	300	150	285	380
Viscosity, SUS @ 100° F.	55-65	97.3	48.1	33-40	50.9	145.1
API gravity	25.3	33.0	33.6	35-40	41.5	13.6
ASTM color	2	1	0.5	<2	0.5	>8
Aromatics, acid treated, vol. percent	26.7	3.6	8.6	21.7	14.7	81.5
Sulfur, wt. percent	1.54	0.06	0.22	0.18	0.06	0.79
Nitrogen, wt. percent	0.02	0.006	0.006	0.007	0.007	0.15
Bromine No.	1.1	0.2	0.8	1.7	7.5	29

¹ This viscosity is given @ 210° F.

Table II

Run	Odor of mixture ¹	Color of mixture ²	Wt. percent of oil lost (cumulative) from mixture after—			
			15 hrs.	45 hrs.	75 hrs.	100 hrs.
5	0	1	0.8	1.9	2.5	3.0
	0	1	0	0	0	0.1
	0	1	0.2	0.5	1.0	1.2
	3	1	9	17	22	24.5
	3	1	1.5	3.5	4.0	4.2
	2	3	0	0	0	0.1

¹ Odor rating of 0 means no odor detected, while a rating of 3 means strong odor detected.

² Color rating of 1 means no discoloration, and color rating of 3 means nitrate was highly discolored.

Various modifications and alterations of this invention will become apparent to those skilled in the art from the foregoing description and examples, without departing from the scope and spirit of this invention, and it should be understood that this invention is not to be limited unduly to that set forth herein for illustrative purposes.

I claim:

1. An explosive composition comprising in admixture ammonium nitrate and oil meeting the following specification:

Pour point, ° F. maximum ----- <50
Flash point, ° F. minimum ----- >250
Viscosity, SUS at 100° F. ----- 30 to 125
30 API gravity ----- 20 to 45
ASTM color ----- <3
Aromatics, acid treated, vol. percent ----- <30
Sulfur content, wt. percent ----- <2
Nitrogen content, wt. percent ----- <0.1
35 Bromine number ----- <2

2. An explosive composition comprising in admixture 92 to 98 weight percent prilled ammonium nitrate and 2 to 8 weight percent of oil meeting the following specification:

Pour point, ° F. maximum ----- <50
Flash point, ° F. minimum ----- >250
Viscosity, SUS at 100° F. ----- 30 to 125
API gravity ----- 20 to 45
45 ASTM color ----- <3
Aromatics, acid treated, vol. percent ----- <30
Sulfur content, wt. percent ----- <2
Nitrogen content, wt. percent ----- <0.1
Bromine number ----- <2

50 3. The explosive composition of claim 2, wherein said ammonium nitrate is 94 to 96 weight percent and said oil is 4 to 6 weight percent.
